INTERNAL COMBUSTION ENGINE

Alois Kreuzer, Augsburg, Germany, assignor to
 Maschinenfabrik Augsburg-Nürnberg A. G.,
 Augsburg, Germany, a corporation of Germany

Application July 22, 1933, Serial No. 681,723
 In Germany August 25, 1932

4 Claims. (Cl. 123—61)

This invention relates to internal combustion engines and more particularly to engines in which there is a stream of air or the like entering the cylinder with an unbalanced cooling effect of the piston rod.

In double-acting, two-cycle Diesel engines, for example, in which the scavenging air enters the cylinder through an opening in the cylinder wall and flows in the general direction of the piston rod, the scavenging air meets only those portions of the piston rod adjacent the piston which are facing the entrance ducts. The portion of the piston rod which is exposed to the scavenging air is therefore more effectively cooled during the time of scavenging air flow than the other side of the piston rod, which is not exposed to the scavenging air current. The heat absorption of the piston rod, however, is almost uniform during the time of combustion, as the injection nozzles are usually arranged symmetrically in the combustion chamber. Due to the even heat absorption at the time of combustion and the uneven cooling effect of the scavenging air, there is a difference in the average temperature of the sides of the piston rod which in time produces a bend in the rod and causes the piston itself to assume a one-sided position productive of unusual wear of one side of the cylinder and piston. The piston rod stuffing box is also unevenly stressed and excessively worn by the bent piston rod. Eventually the extremely unfavorable stressing of the piston rod due to its bend may result in breakage of the rod.

The object of the present invention is to overcome the defects and disadvantages of the prior constructions as above outlined. More effective heating of that portion of the piston rod end which obtains the greatest cooling effect from the scavenging air entering the cylinder is therefore provided.

Other objects and advantages of the invention will be apparent from the following description, the appended claims and the accompanying drawing, in which—

Fig. 1 is a central vertical section of the lower portion of a two-cycle double-acting engine cylinder, embodying the present invention; and

Fig. 2 is a transverse section on the line 1—1 of Fig. 1.

Referring more particularly to the drawing by reference letters, *a* designates the lower portion of the cylinder of a double-acting engine. In accordance with the preferred embodiment of the invention, the engine is of the two-stroke

double-acting Diesel type operating with scavenging air.

Within the engine cylinder *a* is the piston *c*. Secured to the piston is a piston rod *d* extending slidably through the piston rod stuffing box *t* 5 provided in the head or cylinder end *b*. Suitable fuel injection nozzles may be arranged symmetrically in the end head *b* in any customary manner.

Arranged in the cylinder in such a way as to 10 unevenly shield the portion of the piston rod which remains permanently in the combustion chamber is a protective member *g*, preferably a sleeve one side of which is cut away as indicated at *h*. When the piston is at the start of 15 a piston stroke, and in the dotted line position shown in Fig. 1, the protective shield *g* extends from the end head *b* substantially to the lower side of the piston and shields or covers that side of the piston rod which faces away from the flow 20 of scavenging air that obtains through scavenging air inlet ports *e* when the piston is in its full line position as shown in Fig. 1. With the piston in its full line position indicated, the scavenging air flow entering through the inwardly 25 directed ports *e* which are uncovered by the piston, flows toward and past the piston rod and then sweeps down, around and up again before passing out the outlet parts *f*. As the cool flow of air strikes the right-hand side of the piston 30 rod at the point *k* it tends to cool that side considerably more than the other. The shield member *g* is therefore so arranged as to expose that side of the piston rod which faces the inlet ports *e* so that at the time the fuel is injected 35 and combustion takes place there will be a greater heating effect on this exposed portion, and the greater cooling effect that obtains by reason of the scavenging air flow will produce a balance 40 of temperature and a balance of expansion effects and strains. The heat expansion effect in the various portions of the piston rod is therefore substantially uniform over the entire piston rod periphery, and the piston rod therefore effectively maintains its normal straight character 45 over long periods of time.

Attention is directed to the fact that the protective shield or sleeve *g* must unevenly expose that portion of the piston rod remaining permanently in the cylinder at the time of combustion. 50 If the shield fully surrounded and enclosed the entire piston rod end the heat absorption effect at the time of combustion would be balanced or even while the cooling effect produced by the scavenging air would be unbalanced or uneven 55

and the disadvantages that are present in the prior constructions as outlined above would not be avoided.

- 5 In the preferred embodiment of the invention as shown in the drawing, the protective sleeve *g* is fixed with respect to the cylinder end head *b* and with respect to the stuffing box ring *i*. It may be secured directly to the inner end of the stuffing box ring *i* as shown in the drawing, or 10 may be attached to the end head *b* directly or to the piston or piston rod. It is preferred however to attach it to an engine part that is cooled by the cooling jacket provided around the engine cylinder for example as there is thus a more effective 15 heat removal and a better protection or shielding effect is obtained.

While the form of apparatus herein described constitutes a preferred embodiment of the invention, it is to be understood that the invention 20 is not limited to this precise form of apparatus, and that changes may be made therein without departing from the scope of the invention which is defined in the appended claims.

What is claimed is:

- 25 1. In an engine of the character described, an engine cylinder having a transversely extending end head and having an opening in the cylinder wall through which air enters the cylinder, a piston operating in said cylinder, a piston rod fixed to the piston and operating through said end head, the construction being such that one side of the piston rod is cooled to a greater degree than the other side thereof by the air entering the cylinder through said opening, and a member fixed with 30 relation to said end head and projecting into the combustion chamber so as to shield one side of the portion of the piston rod which remains in the combustion chamber at the start of the piston stroke and providing for more effective heating of the side of the piston rod which obtains the greatest cooling effect from the air entering the cylinder through said opening.
- 35 2. In a double-acting two-cycle Diesel engine, an engine cylinder having an end head, and having an opening in the cylinder wall through which scavenging air enters the cylinder, a piston operating in said cylinder, a piston rod fixed to the piston, the construction being such that one side of the piston rod near the piston is cooled to a greater degree than the other side thereof by the scavenging air entering the cylinder, a bushing fixed in said end head and slidably receiving said piston rod, and a protective member fixed to 40
- 45
- 50

5 said bushing and projecting into the combustion chamber so as to provide for exposure of said one side but shielding the said other side of that portion of the piston rod which remains in the combustion chamber at the start of the piston stroke and providing for more effective heating of the side portion of the piston rod which obtains the greatest cooling effect from the scavenging air entering the cylinder.

3. In an engine, an engine cylinder having an end head and having a piston controlled scavenging air inlet opening in one side of the cylinder wall adjacent the piston head when the piston is at the end of the power stroke, a piston operating in said cylinder, a piston rod fixed to the piston and operating through said end head, said air inlet opening being arranged at only one side of the piston rod and so directed as to cause the scavenging air to strike one side of the piston rod near the piston and adjacent said piston controlled opening to cool that side to a greater degree than the other side thereof when the piston is at the end of the power stroke, and a protective member provided within the combustion chamber and providing for exposure of said one side of the piston rod but enclosing the other side of that portion of the piston rod which remains in the combustion chamber at the start of the piston stroke, so as to provide for more effective heating of the side of the piston rod which obtains the greatest cooling effect from the air entering the cylinder through said opening.

4. In a double acting two-cycle engine of the character described, an engine cylinder having an end head extending substantially transversely across the cylinder end and having a scavenging air inlet opening in one side of the cylinder wall adjacent the piston head when the piston is at the end of the power stroke, a piston operating in said cylinder, a piston rod fixed to the piston and operating through said end head, said air inlet opening being arranged to direct scavenging air unsymmetrically towards said piston rod so that one side of the piston rod is cooled to a greater degree than the other side thereof when the piston is at the end of the power stroke, and a stationary member providing for exposure of said one side of said piston rod but enclosing the other side of that portion of the piston rod which remains in the combustion chamber at the start of the piston stroke.

ALOIS KREUZER.
